UNITED STATES PATENT OFFICE.

RAYMOND H. JONES, OF MARYSVILLE, CALIFORNIA.

SEAL LOCK.

Application filed September 11, 1922. Serial No. 587,607.

To all whom it may concern:

Be it known that I, RAYMOND H. JONES, a citizen of the United States, residing at Marysville, in the county of Yuba, State of California, have invented a new and useful Seal Lock, of which the following is a specification in such full and clear terms as will enable those skilled in the art to construct and use the same.

10 This invention relates to a seal lock, and applies to and is an improvement upon my former Patents No. 1,087,020, issued February 10, 1914, No. 1,172,530, issued February 22, 1916, and No. 1,397,587, issued November 22, 1921, and its object is to provide a seal lock that is universal in its application, economical in construction, and automatic in its locking operation.

Seals are used on freight-car doors, on 20 gas, electric and water meters, street car-money boxes, packages containing cigars, and other high priced goods, at time of shipment, on bags of money and high grade ores, on trunks and valises, on milk cans, on 25 crates containing pigeons and poultry, and on mail bags and foreign shipments of various articles.

Some of these articles require the seal shackle to be a cord, and of varying length, 30 when a seal is used thereon; on others a wire shackle or other form of shackle must be used, and to have a seal lock that is universal in its application the seal lock must be of itself of such a character that 35 it can receive and hold securely the free ends of whatever shackle is used, that is, the seal lock must be independent of the shackle.

With the present invention the seal lock is especially adapted to cooperate with a 40 shackle of cord or wire to hold them firmly sealed to whatever they may be fastened, and to the seal lock but several kinds of shackles might be used with this lock.

The seal lock is of itself independent of 45 the shackle in its construction, but cooperates with the shackle to seal the package.

The present invention consists of a slide movable between the walls of a case, which 50 slide cooperates with locking mechanism within the case and with the shackle, to seal the package.

Another feature of the invention is that the slide extends outside the case far enough to enable a tool to engage it when it is 55 to be pulled out, and said slide will receive the identifying characters. This slide

is pulled out of the case a given amount, and is arranged to distort the shackle to secure the lock thereto, thereby simplifying the seal. This distortion makes an operating tool necessary, and at the same time enables a heavy spring to be used which makes the lock more secure.

The encircling shackle is attached to the seal lock through slots on each side of its narrow edges and these slots have a stricture to hold the cord from coming out of the seal lock while the seal lock is being slipped into the proper position on the shackle with respect to the object to be sealed.

The wire is attached to the seal lock by threading it through holes in the walls of the case.

Another object of the invention is to produce a seal which will lock at the time the slide is pulled forward with a spring snap loud enough to be plainly heard, and which spring prevents the return of the slide.

A further object of the invention is to provide a seal effective against clandestine 80 opening so cheap as to enable it to be universally used.

Another object of the invention is to provide a seal which will be so thin that it will hold the shackle in locked position in such a manner that only a very short length of the cord or wire will be engaged, precluding the possibility of cutting or breaking the shackle without it being known.

Other objects of the invention will appear as the description proceeds.

An embodiment of the invention is shown in the accompanying drawings in which the same reference numeral is applied to the same portion throughout, but I am aware that there may be modifications thereof.

Figure 1 is a perspective view of a car door fastening with this seal applied thereto.

Figure 2 is a plan view of the complete seal,

Figure 3 is a plan view of the seal showing it in the locked position.

Figure 4 is a side elevation of the seal shown in Fig. 3,

Figure 5 is a plan view of the seal with the outer cover removed and showing the position of the slide and the spring when locked.

Figure 5^a is a plan view of the top of the lock casing,

Figure 6 is an end view of the locking tool showing a portion of the seal,

Figure 7 is a side elevation of the locking tool showing its application to a seal,

Figure 8 shows the seal as applied to the neck of a bag,

Figure 9 is a plan view of the seal as it appears when wire only is used for the shackle,

Figure 10 is a plan view of the bottom part of the casing blanked and formed into shape,

Figure 10^a is a cross section of Fig. 10 at A—A showing a side view of how the bottom is formed,

Figure 10^b is a cross section of Fig. 10 at B—B another side view of the bottom.

Figure 11 is a plan view of the top part of the casing blanked and formed into shape.

Figure 12 is a longitudinal section on 12—12, Fig. 11,

Figure 13 is a cross section of Fig. 11 at 13—13 showing an end view of how the top is formed.

Figure 14 is a sectional view of the bottom casing of the seal on the line 14—14, Fig. 10,

Figure 15 is a front end view of the case with top and bottom fitted together before the flanges are crimped, and with the slide in position.

Figure 16 is an enlarged sectional view of the edge of the lock casing showing the manner of crimping the upper and lower casing together.

Figure 17 is an end elevation of the complete lock slightly larger than full size,

Figure 18 is a section of the complete seal lock cut in the middle lengthwise, showing spring lock and slide in position before locking,

Figure 19 is a view of the seal equipped for a wire shackle only, with the top removed, and with the slide resting in the bottom before locking showing the arrangement of the holes in the casing with the hole in the slide for bending the shackle,

Figure 20 is a similar view to Fig. 19 after the slide has been pulled to locked condition.

Figure 21 is a sectional view of the seal equipped for cord only, showing the arrangement of the bevelled longitudinal slots in the slide with the opening in the case prior to the slide being moved.

Figure 22 is a plan view of a portion of the casing as illustrated in Fig. 21, with the slide pulled to the locked position.

Figure 23 is an enlarged sectional view of the casing showing the cord in place in the notches therein, on the line 23—23, Fig. 21.

Figure 24 is a sectional view on the line 24—24, Fig. 21,

Figure 25 is a sectional view on the line 25—25, Fig. 22,

Figure 26 is a sectional view on the line 26—26, Fig. 22, showing the slide engaging and locking the cord.

Figure 27 is a plan view of one type of slide intended to operate with the cord only, and having an extension to carry additional identifying characters.

Figure 28 is a plan view of another type of slide intended to operate with the wire only, and having an extension to carry additional identifying characters,

Figure 29 is a perspective view of the locking spring,

Figure 30 to 34 inclusive are diagrammatic views illustrating the operation of securing the wire shackle to the case,

Figure 35 is a section on line 35—35, Fig. 31 showing the wire shackle in place ready to be locked,

Figure 36 is a sectional view on the line 36—36, Fig. 32 showing the wire shackle just ready to be distorted by the slide,

Figure 37 is a sectional view of the slide 85 and casing on line 37—37, Fig. 31, showing the wire shackle in place ready to be locked,

Figure 38 is a sectional view on the line 38—38 Fig. 32 showing the wire shackle as it appears when crowded to one side of the holes of the casing during the process of distorting it, the slide having been pulled forward one-third of its total movement.

Figure 39 is a sectional view on the line 39—39 Fig. 33, showing the wire shackle 95 partially crimped,

Figure 40 is a sectional view on the line 40—40, Fig. 30 showing the wire shackle fully crimped.

The numeral 1 represents the jamb of a door, 2 a door carrying the staple 3, which may be engaged with the hasp 4, a staple 5 holding the hasp in place on the jamb. The door staple is carried by a plate 6 which has a lug 7 depending therefrom, which lug has an opening to receive the shackle 8, which passes through the lug and through a hole in the bolt 9 which secures the door in place.

A pin 10 insures against losing the bolt 9 because the head 11 is slid able thereon.

The seal lock consists of a flat enclosing case made of a bottom 12, a top 13, a slide 28 and a spring 24 which together with a shackle 8 constitutes the seal.

In actual practice the lock casing consists of a piece of sheet metal, such as tin, about $\frac{3}{8}$ " wide, $\frac{1}{16}$ " thick and 1" long, although the size is mentioned only for the purpose of indicating that the seal is intended ordinarily to be a very small and cheap article.

The bottom 12 is formed with a longitudinal depression between walls 62 and 63 (Fig. 14) forming a groove, the walls 62 and 63 merging into side flanges 52 and 55.

The bottom 12 has also a raised portion 43 (Fig. 10^a), a depression or recess 23, and in this depression a raised portion 61.

Bottom 12 is provided with two lateral notches 14 and 15 (Fig. 5) and two holes 16 and 17, although the construction may have 130

either the notches 14 and 15 and not the holes 16 and 17, or the holes and not the notches.

Bottom 12 also has a tongue 58 (Fig. 10) on the forward end and a tongue 56 on the rear end.

The top 13 is formed with a full length raised portion between walls 64 and 65 (Fig. 13), walls 64 and 65 merging into the side flanges 54 and 53 to enclose the slide 28.

Top 13 has also two depressions 45 and 44 (Fig. 12) in its groove, and a raised portion 27.

Top 13 is provided with two lateral notches 19 and 20 (Fig. 5^a) and two holes 21 and 22, although the construction may include the notches 19 and 20 and not the holes 21 and 22, or vice versa.

Top 13 also has a tongue 57 on its rear end (Fig. 11).

The slide 28 (Fig. 27) consists of a thin narrow strip provided with openings 29 and 48, and with two narrow bevelled longitudinally extending slots 50 and 51 cut away 25 to form prongs 30 and 31. The construction may contain the opening 32 and not the slots 50 and 51 together with the openings 29 and 48 as shown in Fig. 28, if desired.

If both types are incorporated in the seal, 30 the slide is lengthened far enough to provide for room to give sufficient metal for strength.

That portion of the slide 28 extending beyond the outer end of the case can be 35 shaped in any manner desired to provide necessary identification marks.

The spring 24 (Fig. 29) is shaped something like a calked horseshoe with the legs curving in and terminating with the points 40 25 and 26, which are turned up at right angles with the legs.

These above named four parts when assembled, comprise the seal lock.

In assembling the parts of the spring 24 45 (Fig. 29) is placed in the recess 23 (Fig. 14) of the bottom 12 with the base of the spring towards the forward or open end of the seal proper (Fig. 18).

This recess is as deep as the spring is 50 thick which brings the legs and the base of the spring on the level of the floor of the bottom casing.

The spring is then held from coming out again by the tongue 58 (Fig. 18) being bent 55 back thereover.

The spring is prevented from slipping forward by the shoulder 66 (Fig. 10^a) resting against the base of the spring, and is prevented from moving backward by reason 60 of the points 25 and 26 of the spring resting against the shoulder 67 of the recess 23.

The slide 28 is then placed within the groove of the bottom formed by walls 62 and 63 (Fig. 14) and in the position is illustrated in Fig. 19, with the points 25 and 26

of the spring 24 meeting without being sprung, the two corners of the opening 48 in the slide, and with these points extending through the opening 48.

The top 13 is then placed on the bottom 70 12 with the shoulders 45 and 44 of the top meeting with shoulders 43 and 61 of the bottom (Fig. 18) and with the flanges 54 and 53 of the top flush with the flanges 52 and 55 of the bottom (Fig. 15). 75

The flanges are then crimped together as illustrated in Fig. 16, and the tongue 56 (Fig. 10) and 57 (Fig. 11) are bent as shown in Fig. 18, closing the rear end.

The openings 14 and 15 in the bottom 12 80 register with openings 19 and 20 respectively in the top 13 (Figs. 5 and 5^a) as do the holes 16 and 17 and 21 and 22 respectively.

After the parts are assembled, it will be seen by referring to Fig. 18 that there is a 85 clearance between the slide and the inside walls of the casing at various points, and at other points the walls of the casing and the slide meet.

The space on the forward end of the seal 90 designated as 59 is to provide a clearance to accommodate a raised identification character on the slide should it be desired to place one there.

The clearance in the back portion of the 95 seal is to accommodate the shackle crimp within the walls of the casing.

The shoulders 45 and 43 together allow for just enough space for the slide to slip between them, while forming on one side a barrier to prevent the possibility of the spring points 25 and 26 being interfered with. The other side of these shoulders forms a complete housing for the spring points, which prevents the spring moving backwards or to the 100 rear even should an effort be made to force or drive the slide back into the case after it was once locked.

The shoulders 44 and 61 together allow for just enough space for the slide to slip 110 between their faces, while forming on one side a barrier to prevent any tool being inserted into the case to disturb the locked condition of the spring with the slide.

The tongue 58 being bent over the base of 115 the spring and within the casing prevents any interference with that portion of the spring.

In the operation of the seal lock the slide 28 is pulled out of the case by the tool 120 a predetermined distance to lock it.

It is prevented from moving farther than the set distance by reason of the upturned points 25 and 26 of the spring meeting the wall 68 in opening 49 of slide 28 (Figs. 19 125 and 20).

The slide is prevented from being accidentally moved out of the position in which it was assembled by reason of the points 25 and 26 of the spring bearing against the 130

slanting walls 69 and 70 of the opening 48 in the slide. The walls of the case frictionally engage the slide at certain points and aid in making it hard to move the slide.

5 As the action of the slide on the shackle to hold the shackle firmly secured requires considerable more effort to move the slide than the power of the hand can give a tool is provided with which to accomplish the results, thereby making it possible to install an unusually heavy locking spring, which otherwise could not be used. This gives additional security to the seal.

10 Lugs 39 and 40 of the lifting tool rest 15 on the forward end of the seal (Fig. 6), with the slide 28 between the lugs, and with the pin 41 through the hole 29 in the slide. The handles 34 and 35 (Fig. 7) are then pressed together which exerts a downward pressure 20 on the lugs 39 and 40 resting upon the end of the seal and an upward pressure on the pin 41 which action pulls the slide 28 a certain distance out of the case. The handles 25 of the tool meet regulating the proper distance the jaws shall move. A pin 36 holds the two sections of the lifting tool together, and the spring 38 holding the handles apart makes the tool always ready for use.

30 As the slide moves forward out of the case 35 the upturned points of the spring 24 follow the slanting sides 69 and 70 of the hole 48 (Fig. 19) towards the points 33, and while the slide has still a very short distance to go the points 25 and 26 of the spring pass by the points 33 into the opening 49 in which opening they snap into their normal position.

35 As the slide has still a short distance to move before completing its movement, walls 40 68 and 71 of opening 49 are spaced far enough apart so as not to interfere with the complete movement of the slide.

45 The slide is held in its extended position by the wall 71 of opening 49 engaging the spring points 25 and 26, which prevent a return movement of the slide.

50 The distance between the points 33 joining the two openings 48 and 49 allows for just a snug clearance for the two upturned 55 points 25, 26 of the spring to pass through, which requires a considerable pressure upon the slide to force the slide by that point, and as the spring points 25 and 26 meet side by side when pinched together, should an attempt to made to pick or tamper with the lock, that barrier will have to be overcome, which will be found to be almost an impossibility.

60 The slide is made to lock a little prior to its completed movement to remove all doubt as to its locking, and while this gives a little back play to the slide it is not enough to affect the secured positions of the shackle with the slide, as that contingency is met 65 in the arrangement of securing the shackle.

An identification character may be placed upon the slide 28 between the opening 29 in the slide and that portion of the slide that rests within the case as designated as space 59 (Fig. 18) to show by its position outside the casing that the strip has moved to locked condition, while the position of the opening 29 at the end of the case can be used to determine the same result.

70 The above methods can be used by those examining the seal after it has been locked, but to the one applying the seal the snap of the spring rebounding into its locked position can be plainly heard.

75 The locking arrangement has been placed in the forward part of the seal ahead of where the shackle is secured to provide for strength of material in the slide to stand immune against any effort to force the slide back into the casing after it has been locked. 80 This feature makes it possible to make the seal of such a short length thereby economizing in material, manufacture and price.

85 When the seal lock is equipped for using the cord shackle 8 alone the construction 90 of the parts is as shown in Figure 21. The openings 15—20 and 46 of the bottom, top and slide respectively make one opening on one side of the case, and openings 14, 19 and 47 of the bottom, top and slide respectively make one opening on the opposite edge of the case.

95 The size of these openings at the bottom are the same as the diameter of the cord, which allows the cord to slide back and forth in the hole prior to the seal being locked to bring the cord up tightly on a bag or other object to be sealed.

100 The cord is forced into these openings from the outside edges through a slight 105 stricture which holds the cord from coming out again.

Figs. 23—24 show the cord in position with the case prior to locking.

110 As the slide moves forward to its locked position the prongs 30 and 31 (more clearly shown in Fig. 27) of the slide gradually close up these openings (Fig. 22) and the cord is forced into the bevelled slots 50 and 51, which pinching or binding operation 115 secures the cord in that position. Fig. 26 illustrates the manner in which the cord is acted upon as the slide has assumed the locked position.

120 The position of the bevelled slots in the slide with the opening in the case when in the locked condition of the slide leave such a narrow opening that should the cord shackle be cut off close to the case for the purpose of tampering with the seal, it cannot be threaded through this hole, or made to appear intact when it is not.

125 Going through the narrow part of the case (Fig. 4) as it does the cord shackle where it is held by the slide is not hid-

den from view, and leaves no doubt as to whether the shackle is all of one piece or not.

The stricture in the case also holds the 5 cord in a position such that the prongs 30 and 31 of the slide pass over the cord and will force the two ends of the cord into the slots.

The straight portion of the slots in the 10 slide is flush with the lower edge of the opening in the case to prevent the cord shackle from being cut as the slide moves forward to locked position.

When the seal lock is equipped for using 15 a wire shackle the case has four small holes that register in pairs (see Fig. 35 showing holes 16 and 17 in the bottom part of the casing which are counterparts of the holes in the top part of the casing) and 20 the slide 28 has a round hole 32 in register with holes in the case.

The holes in the casing are larger than the wire shackle that threads through these holes for reasons that will be explained 25 later.

The hole in the slide registers with both the holes in the casing as shown in Fig. 19 to allow both wire ends to pass therethrough.

Referring to Figs. 31, 35 and 37, it will be seen that when the wire shackle is threaded through the case, because of the spring of the wire and because of the fact that it may be passed around some object, 35 it assumes a position on the outside edges of the holes in the casing.

As the slide 28 moves to locked condition the shackle moves to the inside edge of the holes and towards the center of the hole 40 32 in the slide, see Figs. 36 and 38, or in other words the first third of the movement of the slide the shackle does not move lengthwise of the case but towards the center of the hole in the slide.

As the slide moves still further forward 45 the shackle has assumed the position represented by Fig. 39, and when the final locking position is attained the shackle has taken the bend as represented in Fig. 40, and the position of the hole 32 in the slide 50 with respect to the holes in the casing are as shown in Fig. 20, that is, there is no longer a continuous hole through the casing, which prevents any manipulation of 55 the shackle to create an impression that the shackle is fastened securely when it is not.

To hold the wire shackle securely it must be crimped as shown, yet when the slide 60 has moved to locked condition the solid part of the slide must block an entrance through the case.

To make this combination possible, and not shear the shackle off instead of bending it, the holes in the case are made a little

larger than the shackle is, allowing for a 65 slight amount of play. Together with this arrangement the hole is made round so the shackle can follow its slanting edges for a certain distance as the slide moves forward, adjusting itself gradually to the 70 bending strain, and for this reason the holes in the case meet the hole in the slide as represented by Fig. 19, a little forward of the center and at the extreme edge, and the slide is spaced away from both sides of the 75 casing.

After the slide has moved to locked condition and the shackle is bent in the **U** shaped form, as shown in Fig. 40, it will 80 be noticed that the space within the walls of the case occupied by the shackle is of the necessary width to accommodate the shackle with a close fit, and the shackle being held on the two outside surfaces by the walls of the case, and on the inside of the 85 bend by the slide, there is no chance to work the weave out of the wire and release it from the case.

While the **U** shaped bend in the shackle 90 cannot be seen it can be determined that the wires are intact, for by moving one end of the wire the same wire can be seen to move on the opposite side of the casing.

Whether using a cord to secure the article 95 to be sealed, or using a wire, the wire or cord is placed in the manner desired to properly secure anything and everything on which seals are used, and then this seal lock is used to securely hold the ends of the aforesaid shackle. The material of the lock 100 is heavy enough to stand considerable strains and the slide is thick enough to prevent it from shearing off the shackle.

The term "shackle" applied herein to the 105 wire or cord also includes any inextensible wire, cord, cable, cloth or metal tape used for sealing any car, case or receptacle and one especial advantage of the seal lies in the use of a shackle of any desired length.

What I claim is as follows, but various 110 modifications may be made in the construction shown in the drawings and above particularly described form, within the purview of my invention:

1. In a seal the combination of a casing, 115 a slide projecting therefrom, means to lock the slide in an extended position when it is pulled out of the casing a short distance and means on the slide to secure both ends of a sealing shackle thereto.

2. In a seal the combination of a casing, 120 a slide projecting therefrom, means to lock the slide extended when it is pulled out of the casing a short distance, and means on the slide to distort a shackle to secure it around a given object.

3. In a seal the combination of a casing, 125 a slide projecting therefrom, a spring with-

in the casing to lock the slide extended when it is pulled a short distance out of the casing, and means on the slide to secure two ends of a sealing shackle thereto, with the shackle visible on both sides of the casing.

4. In a seal the combination of a casing, a slide projecting therefrom, a spring to lock the slide extended when it is pulled 10 a short distance out of the casing, and means on the slide to distort both ends of a sealing shackle against said casing when the shackle is passed around an object.

5. In a seal the combination of a flat casing, a flat slide projecting therefrom, a spring within the casing to engage the slide and secure it in a given position when pulled out of the casing further than when in its normal position, and means on the 20 slide co-operating with openings in the casing to distort both ends of a sealing shackle against said casing when pressed against the same by the slide.

6. In a seal the combination of a casing, 25 a slide projecting from the casing, means to lock the slide in an extended position when it is pulled a short distance out of the casing and means on the slide co-operating with the casing to secure both ends of a sealing shackle to the seal.

7. In a seal the combination of a casing, a slide projecting from said casing, the casing having openings therethrough to permit the free movement therein of the ends 35 of a sealing shackle, means on the slide to engage said shackle to secure the latter permanently to the seal, and a spring for locking the slide extended.

8. In a seal the combination of a casing, 40 a slide projecting from the casing having slots at its edges which register with oppositely placed slots in the casing, prongs on the slide positioned to pass through the slots in the casing when the slide is pulled 45 a short distance out of the casing to secure a shackle thereto, and a spring projecting through a hole in the slide to hold it extended.

9. In a seal the combination of a casing, 50 a slide projecting therefrom having openings therein to receive a shackle, and a spring within the casing having two arms passing through the slide to lock said slide extended.

55 10. In a seal the combination of a casing, a slide projecting therefrom, means there-

on to secure both ends of a shackle to the slide and casing, and means to thereupon lock the slide extended.

11. In a seal the combination of a casing, 60 a slide projecting therefrom, means on the slide to indent a shackle to secure it to the casing, and means cooperating with the slide to lock it extended.

12. In a seal the combination of a casing, 65 a slide projecting therefrom, means to lock the slide when it is pulled out of the casing a short distance, the slide and casing having openings to receive a shackle to be secured thereto.

13. In a seal the combination of a casing having openings therein, a slide having openings registering with the openings in the casing, a shackle adapted to be passed through said openings, and means to lock 75 the slide extended, the slide openings being pulled out of register with the casing openings to distort the shackle and secure it thereto.

14. In a seal the combination of a casing 80 having openings, a slide with openings in register with the casing openings, a shackle adapted to pass through the holes when the slide is unlocked and means to lock the slide extended, the openings in the slide and casing being pulled out of register to distort the shackle to secure the shackle and casing together.

15. In a seal, the combination of a casing, 85 a slide therein and projecting therefrom, the casing and slide having openings in register when the slide is unlocked, and means to lock the slide when the openings therein have been moved out of register with the casing openings.

16. In a seal the combination of a casing, 90 a slide carried thereby, the casing and slide having openings normally in register, a shackle passing through said openings, and means to permanently lock the slide in a 100 different position when it has been moved to distort the shackle.

17. In a seal the combination of a casing, 105 a slide carried thereby, the casing and slide having open slots normally in register, a shackle passing through said slots, and means carried by the casing to permanently lock the slide in a different position when it has been moved to distort the shackle.

In testimony whereof I have hereunto set 110 my hand this 22nd day of Aug., A. D. 1922.

RAYMOND H. JONES.
